UNITED STATES PATENT OFFICE.

WILLIAM H. H. KESLER, OF BALTIMORE, MARYLAND.

SASH-CORD GUIDE.

SPECIFICATION forming part of Letters Patent No. 233,254, dated October 12, 1880.

Application filed May 27, 1880. (No model.)

To all whom it may concern:

Be it known that I, WILLIAM H. H. KESLER, of Baltimore city, State of Maryland, have invented certain new and useful Improvements 5 in Sash-Cord Guides; and I hereby declare the same to be fully, clearly, and exactly described as follows, reference being had to the accompanying drawings, in which—

Figures 1 and 2 are, respectively, front and 10 side elevations of the device, and Fig. 3 is a central sectional view of the window-frame and mortising-bit, showing the mode of making the mortise for the insertion of the sash-cord guide.

15 My invention relates to that class of devices known as "sash-pulleys" or "sash-cord guides," consisting, essentially, of a casing in which is mounted a sheave for the reception of the cord that sustains the sash.

20 The object of my invention is to furnish a device of this class so constructed as to dispense entirely with screws or other separate fastening devices, while incidentally affording greatly-increased facility for inserting the 25 sash-cord guide in its mortise, the latter being formed by a single cut of a spurred and laterally-cutting bit.

In the accompanying drawings, A is the casing, in which is mounted, on a suitable 30 pivot-pin, the usual sheave B. The lower edge, C, of the casing is rounded from side to side, as shown, and meets the upper or rear face at a right angle. On the sides of the casing, and at right angles to the lower face or 35 edge, C, are formed flanges or ribs D D'.

In Fig. 3 of the drawings E is the window-frame, and H is a laterally-cutting bit having cutting-spurs I I'.

To form the mortise for the sash-cord guide, 40 the bit is made to approach the window-frame, or vice versa, at an angle equal to that at which the upper or rear edge of the casing A meets the front face, and to traverse a distance accurately equal to the length of the 45 said rear edge, when it is withdrawn in the same path by which it entered. A mortise is thereby formed having a rounded base, G, and grooves F F. The spurs I I' upon the bit H are of such size as to form these grooves 50 of accurately the cross-section of the flanges D D', and the body of the bit is of exactly the same width as the face of the casing A.

It is evident that the mortise thus formed is adapted to receive and retain the described casing, which is simply slid into the mortise 55 in the direction in which the bit was made to enter it, until the rounded base of the casing brings up against the rounded base, G, of the mortise, when the face of the casing will be flush with the face of the window-frame. 60

From the foregoing description of the device and the mode of inserting it it will be readily understood that my invention is not limited to the precise contour of casing shown, although the same is believed to be the best. 65

Keeping in view the ends which I desired to accomplish—viz., to dispense with a separate securing device and to adapt the casing for insertion in a mortise formed by a single cut—certain modifications of my invention at once 70 suggest themselves. A single flange, D, on either side, may be substituted for the pair shown, or more may be added, and the flange or flanges need not of necessity be continued clear across the sides of the casing. 75

Again, the flanges may be curved in the arc of a circle upon the sides of the casing, adapting the device for insertion in a mortise formed by a circular motion of the bit H. When but a single bead or flange on each side of the casing is used it is made to cross the center of the casing and receive the pivot-pin of the sheave. 80

I do not claim, broadly, a sash-cord guide consisting of a pulley-frame one of the cheeks 85 of which is provided with an elongated lug adapted to an inclined groove in one side of the mortise in the window-frame.

What I claim is—

1. A sash-cord guide having lateral flanges 90 upon its casing extending downwardly and rearwardly, as set forth, the device being adapted for insertion into a mortise formed by a laterally-cutting spurred bit, whereby the necessity for a screw or other separate securing device is obviated. 95

2. A sash-cord guide having lateral flanges extending downwardly and rearwardly upon its casing, and having a rounded lower edge, as and for the purpose set forth.

WM. H. H. KESLER.
